191,671

CABINET DOOR RACK FOR PAPER BAGS
OR THE LIKE

Louis M. Kaplan, 1462 Stanley Ave., Los Angeles, Calif.

Filed Mar. 4, 1960, Ser. No. 59,611

Term of patent 7 years

(Cl. D33—3)

FIG. 1 is a front perspective view of a cabinet door rack for paper bags or the like showing my new design; and

FIG. 2 is a vertical sectional view taken on the line 2-2 of FIG. 1, the rack being in open position.

I claim:

The ornamental design for a cabinet door rack for paper bags or the like, substantially as shown.

References Cited in the file of this patent
UNITED STATES PATENTS

920,148 Jackson ----- May 4, 1909
2,745,557 Martin et al. ----- May 15, 1956